CLAIM

The ornamental design for a bicycle basket holder, as shown and described.

DESCRIPTION

FIG. 1 is a front perspective view of a bicycle basket holder showing my design, with portions of a bicycle shown in broken lines and forming no part of the claimed design;

FIG. 2 is a rear perspective view of the bicycle basket holder of FIG. 1;

FIG. 3 is a rear elevational view thereof;

FIG. 4 is a front elevational view thereof;

FIG. 5 is a right side elevational view thereof, the opposite side view of which is a mirror image thereof;

FIG. 6 is a left side elevational view thereof, the opposite side view of which is a mirror image thereof;

FIG. 7 is a top plan view thereof; and,

FIG. 8 is a bottom plan view thereof.
